DESIGN FOR A TRAY FOR DRINKING GLASSES

James S. Hall, Mount Pleasant, Pa., assignor to
L. E. Smith Glass Company, Mount Pleasant,
Pa., a corporation of Pennsylvania

Application February 18, 1943, Serial No. 109,577

Term of patent 7 years

To all whom it may concern:

Be it known that I, James S. Hall, a citizen of the United States, residing at Mount Pleasant, Montgomery County, Pennsylvania, have invented a new, original, and ornamental Design for a Tray for Drinking Glasses, of which the following is a specification, reference being had to the accompanying drawing, forming part thereof.

In the drawing:

Fig. 1 is a top plan view of a tray for drinking glasses, showing my new design;

Fig. 2 is a front elevational view, partly in section; and

Fig. 3 is a side elevational view of the tray illustrated in Fig. 1.

I claim:

The ornamental design for a tray for drinking glasses, as shown.

JAMES S. HALL.
